PROCESS FOR MAKING A LOW SENSITIVITY
PREMIUM GASOLINE

John A. Condrasky, Penn Hills, Pa., and Edwin M. Glazier, Fox Chapel Borough, Pa., assignors to Gulf Research & Development Company, Pittsburgh, Pa., a corporation of Delaware

Filed July 6, 1959, Ser. No. 825,075

1 Claim. (Cl. 208—55)

This invention relates to a process for producing a premium gasoline of low sensitivity and more particularly to such a process employing a combination of catalytic cracking and alkylation.

Our process combines the use of catalytic cracking and alkylation with other refining procedures to produce a premium gasoline of low sensitivity. By "sensitivity" is meant the difference between the research method and motor method octane numbers of the gasoline. We use the shorter terms "research method" and "motor method" to refer to the standard ASTM knock test methods, namely, the Test for Knock Characteristics of Motor Fuels by the Motor Method (ASTM D357) and the Test for Knock Characteristics of Motor Fuels by the Research Method (ASTM D908). High research octane number is desirable for city driving at low engine speeds and with frequent acceleration and high motor octane number is desirable for highway driving at high engine speeds. Premium gasolines now being marketed frequently have high research octane number but unsatisfactorily low motor octane number. The octane rating sensitivity, or in other words, the difference between motor and research octane number is too high. Typical premium gasolines now in use have a sensitivity of 10 or higher. The process of the present invention makes possible the production of premium gasolines, i.e., gasolines having a research octane number (+3 cc. TEL) of 97 or higher, that have a sensitivity of 7.5 or less. This means that for a given research octane number the gasoline has a high motor octane rating. The process of the invention produces high octane gasoline of low sensitivity by a novel combination of procedures for refining various refinery fractions and accomplishes this result at a cost competitive with conventional refining procedures that are unable to produce premium gasoline of low sensitivity.

In processing crude oil for the production of premium gasoline it is known to employ in combination fluid catalytic cracking and alkylation. The catalytic cracking charge normally comprises a straight run gas oil fraction of the crude oil. Conventionally, the aim of the catalytic cracking operation is to produce from the straight run middle distillate or gas oil a maximum yield of gasoline range hydrocarbons. The catalytic cracker is run at a space velocity and temperature providing a cracking severity such that the amount of butenes produced do not exceed the amount that can be alkylated with isobutane recoverable from the crude oil and available for alkylation, a portion of the n-butane recoverable from the crude being required for blending with the final gasoline product to raise its vapor pressure to the required level. In other words, in conventional practice, the severity of the catalytic cracking operation and the consequent yield of light olefins is limited by the yield of butanes from the particular crude oil being processed.

We have now discovered that premium gasoline of unusually low sensitivity can be produced economically by maximizing the alkylation phase of crude oil processing. We can accomplish this result by employing, in combination, high severity fluid catalytic cracking, alkylation, coking of reduced crude and by employing in the alkylation stage butanes obtained from an outside source.

2

In accordance with our procedure, after fractionating the crude oil to obtain straight run gas oil cracking charge and other straight run products, the crude oil residuum is subjected to coking to obtain additional gas oil cracking charge. The catalytic cracking unit is then operated, not at conventional conditions for maximum production of gasoline range hydrocarbons, but at severe conditions to obtain a high yield of C₅ and lighter olefins as alkylation charge stock. In our procedure all of the butenes and at least a portion of the pentenes obtained by catalytic cracking are subjected to alkylation. We employ cracking conditions of severity such that the yield of these olefins exceeds the yield that can be alkylated with the isobutane available directly or indirectly from the crude oil. Accordingly, we use isobutane derived from an outside source for alkylation and thus markedly increase the production of alkylate. The alkylate being a mixture of branched chain paraffins of high motor octane rating contributes greatly as a blending component to our ultimate production of premium gasoline of low sensitivity.

In the preferred embodiment of our process we employ additional processes that yield gasoline range hydrocarbons, some of which yield products rich in branched chain paraffins and, therefore, contribute to production of a high octane premium gasoline of low sensitivity. These additional processes include catalytic isomerization of C₅ and C₆ paraffins, catalytic reforming of straight run naphtha and catalytic polymerization of propylene.

Our process in general comprises charging a total crude oil to fractional distillation to obtain straight run fractions including a gaseous fraction, a C₄ fraction, a gasoline fraction, a gas oil fraction and a residual fraction. The residual straight run fraction is subjected to coking to recover coking products including a fuel gas, propylene, C₄—C₅ olefins, a naphtha fraction, a gas oil fraction and coke. The straight run gas oil fraction and the coker gas oil fraction are subject to fluid catalytic cracking at severe conditions including a temperature of at least 975° F. to achieve conversion of at least 70 volume percent of the fresh cracking charge and thereby to produce C₄ olefins in a molar yield greater than the molar yield of butanes recovered from the straight run distillation of the crude oil and from conversion products of the straight run fractions of the crude oil less the amount of n-butane required for vapor pressure adjustment of the final gasoline products. All of the C₄ olefins and at least a portion of the C₅ olefins produced by fluid catalytic cracking and coking are subjected to alkylation with all of the butanes obtained directly and indirectly from the crude oil and with butanes obtained from another source. In preferred embodiments of the process, straight run gasoline is subjected to catalytic reforming, propylene fractions from catalytic cracking and coking are coking are subjected to catalytic polymerization and a straight run paraffin fraction of the C₅—C₆ range is subjected to catalytic isomerization. A high octane premium gasoline of low sensitivity is produced by blending at least portions of the alkylate, the reforming product and the catalytic isomerization product.

We will describe our process in more detail by reference to the drawing which is a schematic flow diagram of an embodiment of our process.

Total crude oil is fractionated in a conventional atmospheric-vacuum crude distillation unit 10. This equipment comprises an atmospheric fractionating column for topping the crude oil and a vacuum tower for fractionating the topped crude oil to obtain gas oil for catalytic cracking charge stock and vacuum reduced crude for coking charge stock. The products of the atmospheric-vacuum distillation include fuel gas; a C₄ stream of n-butane and isobutane; a C₅ to 190° F. fraction containing n-pentane, isopentane, n-hexane and the branched chain hexanes; a

190° to 375° F. straight run gasoline fraction; a 370° to 620° F. straight run furnace oil fraction; a 620 to 1050° F. heavy gas oil fraction and vacuum reduced crude.

The straight run C₄ fraction is charged by line 11 to the alkylation unit 12. The C₅ to 190° F. fraction is charged by line 14 to the hydroisomerization unit 15. The 190° to 375° F. straight run gasoline fraction is charged by line 16 to the catalytic reforming unit 18. The 375° to 620° F. fraction is charged by line 19 to hydrogen treating unit 20 where it is upgraded for light fuel oil blending. The heavy gas oil fraction is charged by line 21 to the fluid catalytic cracking unit 22. Vacuum reduced crude is charged by line 23 to the delayed coking unit 24.

The coker 24 is operated according to the technique of delayed coking principally to produce gas oil cracking charge from the vacuum reduced crude. In this type of process the reduced crude is heated to a high temperature, e.g., 920° F., and is passed into a coking drum where it is maintained at high temperature for a sufficient length of time to thermally crack or decompose the reduced crude and produce lighter hydrocarbons and coke. Coke forms on the walls of the drum. After one drum is filled with coke the operation is switched to another drum and the coke is removed mechanically or hydraulically from the first drum.

The hydrocarbon stream from the coking drum is fractionated and, as shown in the drawing, several fractions are recovered. A light gas fraction is withdrawn by line 25 as fuel gas. A C₃ fraction rich in propylene is charged by line 26 to the catalytic polymerization unit 28. A C₄ fraction containing n-butane, isobutane, n-butene and isobutylene is charged by line 29 to the alkylation unit 12. A coker C₅ fraction consisting mainly of pentanes and pentenes is charged to gasoline blending by line 30. Preferably, the coker C₅ fraction and a C₅-400° F. gasoline fraction from catalytic cracker 22 are sweetened before gasoline blending in a conventional gasoline sweetening unit 45 wherein objectionable forms of sulfur, e.g., mercaptans, are converted to less objectionable form. A coker naphtha fraction of C₆ to about 400° F. range is charged by line 31 to the hydrogen treating unit 20. The heaviest liquid product of the coking reaction, the coker gas oil which consists of all of the liquid product higher boiling than about 400° F., is charged by line 32 to the fluid catalytic cracking unit 22.

The fresh charge to the fluid catalytic cracking unit 22 thus consists of heavy straight run gas oil charged by line 21 and the coker gas oil, 400° F. plus, charged by line 32. The catalytic cracking unit is a conventional fluid catalytic cracker wherein a suspended bed of powdered silica-alumina catalyst is contacted at high temperature with an upflowing stream of vaporized hydrocarbon charge stock. An essential feature of our process is that the catalytic cracking is carried out at a higher than conventional temperature of at least 975° F. and preferably in the range 975° to 1050° F. The space velocity of the total hydrocarbon charge stock is selected in accordance with the cracking temperature to provide cracking conditions of sufficient severity to achieve conversion of at least 70 volume percent of the fresh cracking charge and thereby to make a high yield of C₅ and lighter olefins.

More specifically, the cracking conditions are of such severity that for a given amount of crude oil charged to the primary distillation unit, the number of mols of butenes produced by catalytic cracking is greater than the number of mols of available butanes obtained from the same amount of crude oil either directly in the straight run C₄ fraction of the crude oil or indirectly by recovery from conversion products of fractions of the crude oil such as the C₄ fraction of the coking products and the C₄ fraction of the reformate. By "available" butanes we mean the amount of isobutane, or of n-butane which can be isomerized to isobutane as needed for alkylation, in excess of the amount required in the form

of n-butane for blending with final gasoline products to obtain the required vapor pressure. Consequently, in accordance with our process, to supply the total amount of isobutane required for alkylation all of the C₄ olefins produced by catalytic cracking of gas oil fractions derived from the crude oil, butane from another source is supplied to the alkylation unit. Such butane is referred to herein as "outside" butane and can be supplied either as isobutane or as n-butane which is isomerized to isobutane as needed.

The butenes produced by catalytic cracking exceed the amount that can be alkylated by the available butanes. Butenes for alkylation are also produced to some extent in the coking unit. Furthermore, at least a portion of the pentenes produced by catalytic cracking are alkylated. Accordingly, a considerable amount of outside butane is required to supplement the available butane for alkyling both sources of butenes and at least a portion of the pentenes from the catalytic cracker. The production of pentenes as alkylation charge is not a deliberate object of our process. However, by operating the catalytic cracking unit at high severity to obtain a high yield of butenes as alkylation charge we also make more pentenes than can be accommodated as blending components of the final gasoline. Accordingly, in our process we subject to alkylation at least a portion of the pentenes produced in catalytic cracking so that the remainder of the C₅ olefins can be accommodated in the gasoline products without exceeding the amounts permitted within the volatility specifications of the gasoline.

As shown in the drawing, the charge to the alkylation unit 12 consists of the straight run C₄ fraction charged by line 11, the C₄ fraction of the catalytic reforming product charged by line 34, the C₄ fraction from the delayed coking unit charged by line 29, the product of isomerization of outside n-butane introduced by line 36 and the C₄-C₅ fraction of the fluid catalytic cracking product introduced by line 37.

The alkylation unit 12 can operate according to any of the known alkylation procedures in which isobutane reacts in equi-molecular proportions with C₄ olefins, and in our process with C₅ olefins, to produce branched chain paraffins having 8 or 9 carbon atoms in the molecule. The schematic drawing omits details of the alkylation process but these are well-known and any of the known procedures and equipment can be used. The feed containing olefins and isobutane, as well as n-butane which is mixed with the isobutane and which passes through the alkylation reactor without being converted, is contacted in the liquid phase with an alkylation catalyst such as a concentrated sulfuric acid catalyst at a temperature of 35° to 45° F. or with a hydrofluoric acid catalyst at a temperature of 45° to 100° F. In order to prevent polymerization and control the alkylation reaction the feed will contain a high ratio of isobutane to olefins, for example, a mol ratio in the range of 3:1 to 6:1. The alkylate stream is deisobutanized and debutanized. The isobutane or a portion thereof can be recycled to the alkylation unit and the n-butane or a portion thereof can be passed by line 38 to the butane isomerization unit 39 to produce isobutane for the alkylation reaction. Alternatively, the n-butane or a portion thereof can be blended with the final gasoline product to control its vapor pressure.

The butane isomerization unit 39 can operate according to any of the known catalytic isomerization procedures. The process can be a low temperature (e.g., 195° to 500° F.) liquid phase isomerization process employing a Freidel-Crafts type of catalyst such as aluminum chloride or it can be one of the more recently developed procedures which employs a solid reforming-type catalyst such as halogen-promoted platinum-on-alumina. In this type of process the butane charge stock is contacted with the catalyst in the vapor phase at high or moderate temperature, e.g., 700°-900° F. in the pres-

ence of hydrogen. The charge stock for the butane isomerization unit will include outside n-butane, that is to say, butane obtained from a source other than the crude oil charged to the atmospheric-vacuum crude distillation unit 19. The outside butane, which is introduced to the isomerization unit by line 52, can be obtained directly or indirectly from other crude oil sources or from natural gas or natural gasoline. The charge to the unit can also comprise recycled n-butane from the alkylation unit and n-butane from various product streams of the process, as shown in the drawing.

In addition to the principal units which have been discussed, e.g., the atmospheric-vacuum distillation unit, the alkylation unit, the fluid catalytic cracking unit and the coking unit, certain other upgrading procedures are employed in the preferred form of our process and these contribute to the production of a high octane, low sensitivity premium gasoline. Thus, the process can employ a catalytic isomerization unit 15 to which is charged, e.g., a straight run C₅-190° F. fraction withdrawn from the distillation unit by line 14. The isomerization unit 15 preferably includes a prefractionator, not shown in the drawing, for separating isoheptanes and heavier from C₅-C₆ paraffins of the C₅-190° F. fraction, the isoheptane and heavier being passed, if desired, to hydrogen treating unit 50 for desulfurization and the C₅-C₆ fraction being charged to the isomerization reactor or reactors of unit 15. Preferably, the C₅-C₆ fraction is fractionally distilled to obtain highly concentrated n-pentane fraction and a fraction highly concentrated in n-hexane and methylpentanes. Then these fractions are separately isomerized, preferably over a halogen-promoted, platinum-alumina catalyst in the presence of hydrogen.

The effluent from the isomerization reactors can be fractionated to recover unconverted n-pentane, n-hexanes and methylpentanes which are recycled to the isomerization reactors. The branched chain paraffin products are blended with the final gasoline product and, being branched chain paraffins of high research and motor octane ratings, they contribute to the low sensitivity of the high octane premium gasoline product of our process.

As we have indicated, the charge to the catalytic reforming unit 18 comprises the straight run 190° to 375° naphtha fraction withdrawn from the atmospheric-vacuum distillation unit by line 16. Another suitable reforming charge stock is the fraction of similar boiling range obtained by hydrogen treating a C₆ to 400° F. fraction of the coking product. This fraction is subjected to mild hydrogen treatment in the hydrogen treating unit 20 by contact with a hydrogenation catalyst such as cobalt molybdate on alumina in the presence of hydrogen at a temperature of 600° to 800° F. Specific conditions suitable for this hydrogen treatment include a temperature of 675° F., a pressure of 600 pounds per square inch gauge, a liquid hourly space velocity of 8 volumes per volume per hour and a hydrogen circulation rate of 4,000 standard cubic feet per barrel with a hydrogen consumption of 200 standard cubic feet per barrel. The hydrogen treatment saturates and desulfurizes the coker naphtha but reduces its octane rating. The hydrogenated coker naphtha requires octane improvement before it can be satisfactorily employed as a premium gasoline component. Accordingly, the hydrogen treated fraction is charged by line 40 to the catalytic reformer 18.

The catalytic reformer can be any of the conventional units employed for upgrading naphtha fractions wherein such reactions as aromatization, dehydrogenation, isomerization and hydrocracking occur. The naphtha charge stock is contacted with a reforming catalyst such as platinum-alumina or molybdena-alumina in the presence of hydrogen at elevated pressure and temperature, e.g., 400 to 600 pounds per square inch gauge and 850° to 950° F. The reformate is fractionated to separate a hydrogen-rich gas which is recycled to the reforming unit 75

and a C₄ fraction which can be passed by line 34 to the alkylation unit 12. The reformate withdrawn by line 41 is of high octane rating and is charged to the final gasoline product blending unit.

5 Another unit employed in the preferred form of our process is the catalytic polymerization unit 28. In this unit the various olefinic C₃ streams produced in the process are contacted with a polymerization catalyst such as phosphoric acid to polymerize the propylene and produce an olefinic polymer gasoline which, because of its rather high octane sensitivity, is used as a blending component for the regular grade gasoline rather than for the premium grade gasoline.

An important stage of our process is the blending of 15 the gasoline components. Products available for gasoline blending include alkylate from alkylation unit 12; reformate from reforming unit 18; sweetened gasoline, including the sweetened coker C₅ fraction and the sweetened FCC C₅-400° F. fraction from sweetening unit 45; isopentane and branched chain hexanes from C₅-C₆ isomerization unit 15; and polymer gasoline from catalytic polymerization unit 28. To adjust vapor pressure to the required level, e.g., to a Reid vapor pressure of 10 pounds per square inch, n-butane is added to the gasoline blend. This can be n-butane recovered from the alkylation unit 12 and/or outside n-butane.

Besides the above main gasoline components other products for gasoline blending include a small amount of pentanes recovered from the butane isomerization product of unit 39 and the hydrogen-treated gasoline fraction from hydrogen treating unit 50. In the latter unit a light gas oil from catalytic cracking and a C₇+ fraction from the isomerization unit 15 prefractionator are desulfurized by contact with hydrogen and a hydrogenation catalyst, e.g., cobalt molybdate on alumina, at, for example, 700° F., 600 p.s.i.g., space velocity of 4 vol./vol./hr. and hydrogen rate of 4,000 s.c.f./bbl.

The other principal liquid product of our process is No. 2 fuel oil. This product is formed by blending the hydrogen-treated light FCC gas oil from hydrogen treating unit 50; the hydrogen-treated coker naphtha, 370° to 400° F. and straight run furnace oil from hydrogen treating unit 20. Other products of our process include fuel gas which is recovered from the different units as indicated and petroleum coke obtained from delayed coking unit 24. Another product is heavy gas oil recovered from catalytic cracking unit 22. If desired, this product can be fractionated to obtain a light fraction suitable as No. 5 fuel oil and a heavy fraction which is employed as refinery liquid fuel.

From the above description it can be seen that butanes are employed for two ultimate purposes in our process. They are used to provide isobutane for alkylation with the C₄ and C₅ olefins in the alkylation unit 12 and to provide 55 n-butane for blending with the final gasoline product to raise the vapor pressure thereof to the required level. We have shown that the sources of the butanes include a straight run C₄ fraction obtained directly from the crude oil and other streams obtained indirectly from the crude oil such as a C₄ stream from the delayed coking unit 24, a C₄ stream from the fluid cracking unit 22, an isobutane stream from the butane isomerization unit 39 and a C₄ stream from the reforming unit 18.

The other source of butane is the outside butane stream 65 52 which can be obtained, for example, from another crude oil or from natural gas or natural gasoline. We refer throughout this specification to the fact that the catalytic cracking unit is operated under conditions of such severity as to yield a greater amount of C₄ olefins than can be alkylated with the available isobutane obtained directly and indirectly from the crude oil. By this we mean that the amount of butanes obtained from the particular crude oil is insufficient to supply isobutane for alkylating all of the C₄ olefins produced in the catalytic cracking stage and to provide butanes as required for

blending with the final gasoline products. Consequently, an outside butane stream is introduced into the process. It should be understood that the outside butane can be used either for gasoline blending or can be isomerized and used for alkylation. If the outside butane stream is employed for gasoline blending, it may very well be that the butanes obtained directly and indirectly from the crude oil will be sufficient for alkylation but, the amount will be inadequate to supply the over-all requirement. Therefore, it should be understood that when we refer to the fact that the fluid catalytic cracking stage is carried out at such severity as to yield a greater amount of C₄ olefins than can be alkylated with the isobutane obtained from the crude oil, we are defining the relative yields of butanes and of C₄ olefins. Whether the butanes obtained from the crude oil are employed for alkylation or for final product blending is immaterial. The important fact is that outside butanes must be added to the butanes obtained from the crude oil to meet the over-all requirement for alkylation and gasoline blending.

The following example illustrates results obtainable with our process.

8 EXAMPLE

In this example, 100,000 barrels per calendar day (hereinafter abbreviated as b./c.d.) of Kuwait crude oil of 31.5° API gravity is processed by our new procedure to produce regular and premium grade gasolines in a volume ratio of 40 to 60. In this operation the fluid catalytic cracking unit operates at a temperature of 975° F. and achieves 71.5 percent conversion of the fresh cracking charge which consists of straight run and coker gas oil fractions. An outside butane stream is introduced into the system at a rate of 3,406 b./c.d. The yield of premium gasoline having a research octane rating (TEL content: 2.7 cc./gal.) of 102.7 and a sensitivity of 7.5 is 22,892 b./c.d. The yield of regular gasoline having a research octane rating (TEL content: 2.7 cc./gal.) of 95.7 and a sensitivity of 11.2 is 34,337 b./c.d. Details as to the charge and product streams for each of the process units are given in Tables I through IV below. In the tables the yields of gaseous products such as fuel gas are reported as barrels per day of fuel oil equivalent, the latter being abbreviated in the tables as "FOE."

In Table I we have shown all of the gasoline components as being charged to the gasoline blending stage for premium and regular gasoline products. In actual practice the components or their proportions will be different for the premium and regular grade products. Table III below illustrates amounts of the various gasoline components of Table I that can be employed in forming premium gasoline and regular gasoline in our process when processing 100,000 b./c.d. of Kuwait crude. Table III also lists the octane numbers of these products. All data in this table are reported on the basis of 10 pounds Reid vapor pressure. In other words, the amount of each gasoline component reported in Table III includes butanes in an amount sufficient to raise the Reid vapor pressure of

the component to 10 pounds per square inch absolute. Since butanes are included with various gasoline components the butanes are not listed as a separate component as in the blending stage of Table I.

Motor, +2.7 cc. TEL./gal.	84.5
Sensitivity	11.2

Table III illustrates one suitable blending combination for the different gasoline components produced in our process. In this particular blending scheme all of the high yield of 10,302 b./c.d. of alkylate is used in the premium gasoline product. Since our process produces other fractions rich in branched chain paraffins, e.g., branched chain C₅ and C₆ paraffin fractions and light reformate, and since the branched chain paraffins have good research and motor octane ratings, it is possible to vary the combination considerably and still produce a high yield of premium gasoline of very high research octane rating and low sensitivity.

We have indicated that our process produces high octane gasoline of low sensitivity at a cost competitive with conventional refining procedures that are unable to produce premium gasoline of low sensitivity. Furthermore, our process achieves this result at lower cost per gallon than other procedures aimed at producing high octane gasoline of low sensitivity. This can be demonstrated by comparison of the embodiment of our process as described in the foregoing example and in Tables I, II and III, with the results of other procedures which are intended for producing high octane premium gasoline and which employ certain process elements in common with our process. One such process, which we will refer to as process A, employs atmospheric-vacuum distillation, delayed coking of vacuum bottoms, fluid catalytic cracking of straight run and coker gas oils, catalytic polymerization of propylene, alkylation of butylenes with isobutane, catalytic reforming of straight run naphtha and hydro-treated coker naphtha, as well as such additional elements as hydro-treating and gasoline sweetening of fractions similar to those that are subjected to such treatments in our process. An essential difference between process A and our process in the embodiment described in the example and tables is that in process A the fluid catalytic cracking unit is operated under conventional conditions to achieve 65 percent conversion whereas in our process the fluid catalytic cracking is carried out at 975° F. to achieve 71.5 percent conversion. As a result, in process A outside butanes are not required for alkylation of the C₄ and C₅ olefins produced by fluid catalytic cracking. The butanes obtained from the crude oil are adequate for the alkylation stage and for vapor pressure adjustment of the gasoline products. Other differences are that the preferred form of our process employs hydroisomerization for upgrading low octane rating C₅ and C₆ paraffins and employs butane isomerization for isomerizing either outside n-butane or n-butane obtained from the crude oil whereas process A does not.

In still another comparable operation which we designate as process B most of the procedures employed in our process are employed but, instead of fluid catalytic cracking, process B employs thermal cracking of straight run and coker gas oils. In process B all of the butanes employed for alkylation and gasoline blending are obtained directly or indirectly from the crude oil.

A comparison of the results obtainable in our process and in processes A and B is given in Table IV below. The table lists yields of various products in processing of 100,000 b./c.d. of Kuwait crude for production of premium and regular gasolines in a 60:40 ratio and shows the comparative costs per gallon of the gasolines produced.

Table IV

	Invention	A	B
5 Premium gasoline (10 RVP): Yield, bbl./100,000 bbl. crude	22,892	20,827	19,386
Octane ratings: Research, +2.7 cc. TEL./gal.	102.7	101.0	101.3
Motor, +2.7 cc. TEL./gal.	95.2	88.0	94.3
Sensitivity	7.5	13.0	7.0
10 Cost, cents/gallon	13.93	13.60	14.67
Regular gasoline, (10 RVP): Yield, bbl./100,000 bbl. crude	34,337	31,241	29,078
Octane ratings: Research, +2.7 cc. TEL./gal.	95.7	94.0	94.3
Motor, +2.7 cc. TEL./gal.	84.5	86.2	87.3
Sensitivity	11.2	7.8	7.0
15 Cost, cents/gallon	11.93	11.60	12.67
Alkylate yield, b./c.d.	10,302	4,766	4,195

Table IV shows that process A makes a premium gasoline at slightly less cost than our process but the sensitivity is 13.0 as compared with 7.5 for our process and the research octane number is only 101.0 as compared with 102.7 for our process. In process B the sensitivity of the gasoline is low but the research octane rating is lower than in our process and the cost is substantially higher. With respect to the regular grade gasoline products, the product of our process has a higher research octane rating than that of either process A or B and the cost per gallon for our product is almost as low as that of process A and is substantially lower than that of process B. From these results it can be seen that our process is markedly superior economically to other methods of making high octane premium gasoline of low sensitivity. A major difference between our process and the other two processes is seen in the alkylate yield as reported in Table IV. For a crude charge of 100,000 barrels the alkylate yield for our process is 10,302 barrels as compared with only 4,766 barrels for process A and 4,195 barrels for process B.

The foregoing example and tables show that we have developed a valuable new combination of refining procedures for producing a high yield of high octane rating premium gasoline of low sensitivity. We accomplish a new result through a new combination of procedures which include (1) the use of high fluid catalytic cracking temperature to produce maximum butenes for use as alkylation charge stock, the fluid catalytic cracking unit being operated at 975° F. or higher to achieve conversion of the cracking charge of at least 70 volume percent, (2) alkyllating total butene production, plus a portion of the pentenes to the extent required by gasoline volatility restrictions, and (3) isomerizing outside butane to provide adequate isobutane for alkylation.

Obviously many modifications and variations of the invention as hereinbefore set forth may be made without departing from the spirit and scope thereof and therefore only such limitations should be imposed as are indicated in the appended claim.

We claim:

A process for making low sensitivity premium gasoline which comprises:

60 fractionally distilling a total crude oil to obtain a straight run C₄ fraction, a straight run C₅ to 190° F. light gasoline fraction, a straight run gas oil having an initial boiling point of about 620° F. and a straight run residuum;
65 coking said straight run residuum, and recovering conversion products including C₄ olefins, n-butane, isobutane, a coker gasoline fraction and coker gas oil; subjecting said straight run gas oil and said coker gas oil to fluid catalytic cracking and recovering conversion products including C₄ olefins, n-butane, isobutane, C₅ olefins and a cracked gasoline fraction; said fluid catalytic cracking occurring at severe conditions, including a temperature of at least 975° F., sufficient to achieve conversion of at least 70 volume

13

percent of said catalytic cracking charge to produce a molar yield of C_4 olefins greater than the number of mols of n-butane and isobutane recovered by straight run fractionation of said crude oil and by fractionation of said conversion products minus the mols of butanes required for vapor pressure adjustment of the final gasoline products;

subjecting all of said C_4 olefins produced by said fluid catalytic cracking and coking operations and at least a portion of the C_5 olefins produced by said fluid catalytic cracking to alkylation with all of the isobutane obtained directly and indirectly from fractionation of said crude and said conversion products and

5

14

with isobutane from another source and recovering an alkylate therefrom; and blending said alkylate with said aforementioned gasoline fractions to produce a premium gasoline having an octane rating sensitivity no greater than 7.5.
